UNITED STATES PATENT OFFICE

JAMES G. MILLER, OF BUFFALO, NEW YORK

BURIAL VAULT

Application filed October 23, 1931. Serial No. 570,730.

This invention relates to burial vaults and has for its primary object to provide, in a manner as hereinafter set forth, a device of this character embodying an end closure and including novel means for locking and sealing said end closure in position.

Other objects of the invention are to provide a burial vault of the aforementioned character which will be simple in construction, strong, durable, and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:

20 Figure 1 is a view in horizontal cross section through a burial vault in accordance with the present invention with the end closure in position.

Figure 2 is a view in top plan showing the 25 end portion of the vault in which the closure is disposed.

Figure 3 is a view in end elevation of the invention.

Figure 4 is a view in vertical cross section 22 through the closure and the end portion of the vault in which the closure is mounted.

Figure 5 is a sectional view taken substantially on the line 5—5 of Figure 3.

Figure 6 is a sectional view taken substantially on the line 6—6 of Figure 3.

Figure 7 is a view in horizontal cross section taken substantially on the line 7—7 of Figure 3.

Figure 8 is a detail view in perspective of 40 one of the locking bars.

Referring now to the drawings in detail, it will be seen that the burial vault constituting the present invention is designated generally by the reference numeral 1, the same 45 being preferably of concrete and comprising a bottom 2, side walls 3, a top 4 of arcuate cross section, and a closed end 5. The other end of the vault is open.

The top 4, at the open end of the vault, is 50 provided with the relatively offset, diagonal

faces 6 and 7 which are connected by the face 8. The end closure which is designated by the reference numeral 9, is provided with an arcuate upper end having the diagonal or beveled, relatively offset faces 10 and 11 connected by the face 12. The face 10 of the closure 9 is adapted for abutting engagement with the face 6 of the top 4 and the face 11 of said closure 9 is adapted for abutting engagement with the face 7 of the top 4. The faces 8 and 12 are spaced from each other and, as clearly seen in Figures 4 and 6 of the drawings, an arcuate chamber 13 is provided across the upper portion of the vault, said chamber 13 being of polygonal cross section 65 and having a passage 14 extending therefrom to the upper surface of the top 4.

At the open end of the vault the side walls 3 are provided with the diagonal or beveled, relatively offset surfaces 15 and 16 which are connected by a channel 17. The vertical sides of the end closure 9 are formed with the diagonal or beveled, relatively offset faces 18 and 19 which are connected by a channel 20. The face 18 is adapted for abutting engagement with the face 15 and the face 19 is for abutting engagement with the face 16. The channel 20 is thus disposed in opposed relation to the channel 17. Thus it will be seen that the channels 17 and 20, in conjunction with each other, provide substantially rectangular passages which extend the entire vertical length of the end closure 9 on each side thereof. These passages are designated by the reference numerals 21. The top 4 is provided with 80 passages 22 disposed vertically and which constitute extensions for the passages 21. The passages 13, 14, 21, and 22 all have communication with each other.

The bottom 2 of the vault is provided, at the open end of said vault, with a transverse channel 23 the outer wall of which is constituted by a flange 24 having an inclined or beveled top 25. The lower end and inner side of the end closure 9 is adapted for abutting engagement with the bottom of the channel 23 and the inner wall thereof, as clearly seen in Figure 5. The outer portion of the lower end of the end closure 9 is inclined or beveled, as at 26, for engagement 95 100

on the inclined or beveled face 25 of the flange 24. The beveled or inclined face 26 merges with the relatively angularly disposed faces 27 and 28 which, in conjunction with the bottom and outer walls of the channel 23 of the bottom 2 define a passage 29 communicating, at its ends, with the lower ends of the passages 21.

It will thus be seen that a continuous passage around the end closure 9 has been provided. The reference numeral 30 designates elongated locking bars of any suitable material, preferably metal, having any desired number of holes 31 therein. On one side, the lower end portion of the locking bar 30 is beveled, as at 32. The locking bars are inserted in the passages 21 through the extension passages 22, said locking bars being disposed diagonally in the passages 21 and having one longitudinal edge engaged in the outer corner of the channel 17 and the other longitudinal edge engaged in the inner corner of the channel 20 of the end closure 9. The locking bars 30 are of a width to fit snugly diagonally in the passages 21 and as said locking bars are driven downwardly into the passages the longitudinal edge thereof which is beveled, as at 32, engages the end closure and forces the same into position. Suitable sealing material 33 is then poured into the passages 21 and 29 through the extension passages 22 and into the passage 13 through the passage 14 or, if desired, all of the passages may be substantially filled through the passage 14.

If necessary or desirable to facilitate the sealing operation, and in cold weather, a heating element or wire 34 may be disposed around the edges of the end closure 9 in a manner to be disposed in the passages 13, 21 and 29 after the end closure has been disposed in position. This element is then connected with a suitable source of electric current supply by any suitable means for heating the same for the purpose of preventing freezing of the sealing compound while the same is being poured into place so that the compound is set, formed and workable until it is in position, after which the connection from the wire to the electrical source is disconnected from the wire. In addition, the heating element or wire 34 constitutes a reinforcement for the sealing compound, as will be apparent.

55 A fitting F is anchored in one of the passages 22 for connecting a pressure gun of injecting the sealing medium. During this injecting operation the other passage 22 and the passage 14 may be plugged by suitable means (not shown).

It is believed that the many advantages of a burial vault in accordance with this invention will be readily understood, and although the preferred embodiment of the invention is as illustrated and described, it is

to be understood that changes in the details of construction and in the combination and arrangement of parts may be resorted to which will fall within the scope of the invention as claimed.

What is claimed is:

1. A burial vault open at one end, a closure for the open end of the vault, the marginal edges of the closure and adjacent portions of the vault being beveled and having channels therein constituting, in conjunction with each other, passages for the reception of a sealing medium, and locking bars disposed in the side passages and each having one edge engaged with the vault and the other edge engaged with the closure for retaining said closure in position, the channel in the bottom of the vault being of considerable width and the lower edge of the closure having a flange at its rear fitting in the rear part of the last-mentioned channel, said flange leaving the front part of the channel open.

2. A burial vault open at one end and including a top, bottom, side walls, and an end wall, a closure for the open end of the vault, the marginal edges of the closure and the adjacent portions of the vault having channels therein constituting, in conjunction with each other, communicating passages extending entirely around the closure for the reception of a sealing medium, and elongated, perforated locking bars disposed in certain of the passages and having one longitudinal edge engaged with the vault and the other longitudinal edge engaged with the closure for securing said closure in position.

3. A burial vault open at one end, a closure for the open end of the vault, certain of the marginal edges of the closure and adjacent portions of the vault having pairs of relatively offset, beveled faces for abutting engagement with each other when the closure is in position, said marginal edges of the closure and adjacent portions of the vault further having opposed channels therein connecting the beveled faces, and, in conjunction with each other, constituting passages of polygonal cross section, and elongated, flat locking bars disposed in the passages and having one edge engaged in a corner of the vault channels and their other edges engaged in the diagonally opposite corners of the closure passages for securing the closure in position.

In testimony whereof I affix my signature. JAMES G. MILLER.
